United States Patent Office

Des. 201,055
Patented May 4, 1965

201,055

TRASH CAN

Herman M. Ebert, 1013 Central Ave., Highland Park, Ill.

Filed Aug. 18, 1964, Ser. No. 81,335

Term of patent 14 years

(Cl. D58—17)

FIG. 1

FIG. 4

FIG. 2

FIG. 5

FIG. 3

I claim:

The ornamental design for a trash can, as shown.
